Filed Sept. 11, 1957, Ser. No. 683,312

8 Claims. (Cl. 83—133)

My invention relates to a high-pressure, hydraulic, piercing cylinder and more particularly to an improved, high-pressure, hydraulic, piercing cylinder having an integral booster and stripping means.

Hydraulic power cylinders for pushing a punch or the like through a workpiece are known in the prior art. These assemblies are provided with an automatic means for holding a stripper plate against the work while the punches are being withdrawn or stripped from the work. One form of such an assembly is disclosed in the patent to C. E. Novinger et al., No. 2,758,652, issued August 14, 1956, for a hydraulic punch and stripper. In these punch and stripper assemblies fluid under pressure moves a power piston and cylinder relative to each other to move the punch holder toward the work. At the same time the fluid under pressure moves a stripper plate into engagement with the work to hold the work firmly in position during the punching operation. After the stripper plate engages the work and before the punches enter the work, it is necessary to boost the pressure within the cylinder in order to drive the punches through the work. To accomplish this in systems of the prior art a separate booster external to the piston and cylinder assembly is employed. It will be appreciated that high-pressure pipes are required to carry fluid from the booster to the piston and cylinder assembly. This system of the prior art is expensive and the possibility exists that leaks will develop under the action of the high-pressure fluid.

I have invented an improved hydraulic punch and stripper assembly which is provided with an integral booster for raising the fluid pressure by an amount necessary to drive the punches through the work. My assembly does not require the external booster employed in systems of the prior art. My system does not require that fluid under high pressure be conducted through any pipes external to the punch and stripper assembly. For this reason my assembly is less expensive and is less likely to develop leaks than are the systems of the prior art.

One object of my invention is to provide a high-pressure, hydraulic, piercing cylinder having an integral booster and stripping means.

Another object of my invention is to provide a high-pressure, hydraulic, piercing cylinder which does not require the external booster of systems of the prior art.

A further object of my invention is to provide a high-pressure, hydraulic, piercing cylinder which does not require fluid under a high pressure to flow through any pipe external to the cylinder.

A still further object of my invention is to provide a high-pressure, hydraulic, piercing cylinder which is less expensive.

Yet another object of my invention is to produce a high-pressure, hydraulic, piercing cylinder which is less likely to develop leaks than are systems of the prior art.

Other and further objects of my invention will appear from the following description.

In general, my invention contemplates the provision of a high-pressure, hydraulic, piercing cylinder formed with

2

a power chamber and with a stripper chamber. I dispose a stationary power piston within the power chamber and a movable stripper piston within the stripper chamber. My stripper piston has a head, on which fluid admitted into the stripper chamber may act, and an end extending into a bore in the wall separating the cylinder chambers. Fluid under pressure admitted to the power chamber on one side of the power piston head moves the cylinder assembly toward the work. This fluid also acts on the small face of the piston to move the piston into engagement with the stripper pins which hold a stripper plate against the work. After the stripper plate contacts the work the increased resistance moves the stripper piston relative to the cylinder to build up a back pressure in the power chamber and supply line to actuate a sequence valve to admit fluid under pressure to the stripper chamber on the side of the stripper piston head in engagement with the stripper pins. This fluid acts on the relatively large area of the stripper piston head to cause a buildup or boosting of the pressure in the power chamber through the medium of the smaller area face of the stripper piston to provide the pressure required to drive the punches through the work. At the same time, this fluid under pressure maintains the stripper plate in engagement with the work. A check valve in the supply lines prevents this boosted pressure from backing up into the supply lines. When the punching operation is complete, direction of the fluid flow in the supply line is reversed, the punch is stripped from the work and the assembly is returned to its initial position.

In the accompanying drawings, to which reference is made in the instant specification and which are to be read in conjunction therewith and in which like reference numerals are used to indicate like parts in the various views:

Figure 1 is a schematic view of my high-pressure, piercing cylinder and its associated fluid system.

Figure 2 is a sectional view of my high-pressure, piercing cylinder showing the relative positions of the parts before a punching operation is begun.

Figure 3 is a sectional view of my high-pressure, piercing cylinder showing the relative positions of the parts as the cylinder moves toward the work.

Figure 4 is a sectional view of my high-pressure, piercing cylinder showing the relative positions of the parts during the course of a punching operation.

Figure 5 is a sectional view of my high-pressure, piercing cylinder showing the relative position of the parts during the return stroke of the cylinder.

Referring more particularly to Figure 1 of the drawings, my high-pressure, piercing cylinder has a cylinder body 10 separated into a power chamber 12 and a stripper chamber 14 by a partition 16 formed in the bore of the body 10.

An end cap 18, secured to an end of the body 10 by any convenient means such as bolting or the like, closes the end of the power chamber 12. A power piston rod 20 passes through a bore 22 in cap 18. Cap 18 houses a power piston head 24 formed on rod 20 within chamber 12.

The press with which our cylinder is used includes a frame, indicated generally by the reference character 26, having an upright heel block 28 on which we mount the power piston rod 20 by any convenient means (not shown). We provide frame 26 with a guideway 32 on which the cylinder 10 rides in its movement toward and away from the work.

A punch-carrier tool head 34, secured to the end of body 10 remote from cap 18 by any convenient means such as bolts 36, closes the stripper chamber 14 to house a booster and stripper piston 38 formed with a rod 40 which extends into a bore 42 formed in separator 16.

From the foregoing it will be seen that a fluid under pressure admitted into chamber 12 on that side of head 24 which will cause body 10 to move to the right as viewed in Figure 1, also will act on the end face 44 of rod 40 to move head 38 to the right, as viewed in the figure. Conversely, fluid pressure admitted to chamber 14 between head of stripper and booster piston 38 and tool head 34 is transmitted by rod 40 to chamber 12 through the medium of the face 44. Owing to the relatively large area of head of stripper and booster piston 38 with respect to this face 44, a multiplication of pressure results in the course of transmission of pressure by rod 40.

Bolts 46 screwed into tool head 34 have smooth shanks 48 which slidably support a stripper plate 50 for movement along shanks 48. Stripper pins 52 extending through the tool head 34 and through the punch holder, to be described hereinafter, are adapted to transmit pressure from stripper and booster piston 38 to stripper plate 50.

A screw 54 secures the punch holder 56 to the tool head 34. The punch holder 56 supports the tools such as punches 58 which are required to perform the necessary operations on a work piece 60 supported on the frame by any convenient means (not shown) known to the art. I form the stripper plate 50 with bores 62 through which punches 58 pass in the course of a punching operation.

Frame 26 also carries a guide 64 having bores 66 into which punches 58 push slugs or piece parts 68 formed in the course of a punching operation. Bores 66 are open to permit the slugs 68 to fall out of the die to a scrap collector or the like (not shown).

I form rod 20 and heel block 28 with a first passage 70 through which fluid under pressure may be admitted to chamber 12 between head 24 and separating wall 16. A second passage 72 formed in rod 20 and in heel block 28 provides a path for the flow of fluid to chamber 12 between head 24 and plate 18.

My fluid supply system includes a motor 74, which drives a pump 76 through the linkage 78 to draw fluid from a tank 80 through a pipe 82. Pump 76 supplies fluid under pressure to a pipe 84 to which I connect a relief valve 86 which permits the fluid to flow back into the tank when the pressure within pipe 84 exceeds a predetermined pressure. A control valve, indicated generally by the reference character 88 has a housing 90 provided with a port 92 communicating with pipe 84. The valve spool 94 includes respective heads 96 and 98 which, in the central position of spool 94 shown in Figure 1, close respective outlet ports 100 and 102 connected to pipes 104 and 106. Spool 94 is adapted to be actuated in any convenient manner known to the art to move to the left or to the right of the intermediate position shown in Figure 1. In the left position of spool 94 a communication is established between supply pipe 84 and pipe 104. At the same time fluid from pipe 106 is permitted to flow through housing 90 and through an outlet pipe 108 to the tank.

In the position of spool 94 to the right a communication is established between pipe 106 and supply pipe 84 while fluid in pipe 104 is permitted to flow through the valve body and through a pipe 110 to the tank. I connect pipe 104 to one inlet port 112 of a pilot-operated check valve indicated generally by the reference character 114, having a housing 116 formed with a chamber 118 provided with a seat 120. A spring 122 normally seats the piston 124 of valve 114 on seat 120. A port 126 formed in housing 116 is adapted to admit fluid under pressure to the housing to act on a piston 128 which contacts piston 124 to lift the body off seat 120. The pipe 127 connects port 126 to pipe 106. The fluid acting on piston 128 moves the piston 124 upwardly, as viewed in Figure 1, to permit fluid in the chamber 12 to flow outwardly through passage 70, through a port 130 formed in housing 116 and past seat 120 to pipe 104.

The hydraulic system of my piercing cylinder includes

a sequence valve indicated generally by the reference character 132 having a housing 134 formed with a port 136 for conducting fluid from a pipe 138, connected to pipe 104, the chamber 140 formed by housing 134. A spring 142 disposed in housing 134 normally positions the valve spool 144 to close a port 146 formed in the wall of the housing 134. A pipe 148 connects port 146 to passage 150 formed by the cylinder body 10. Passage 150 affords a communication between pipe 148 and chamber 14 between the stripper and booster piston 38 and tool head 34. A passage 152 formed in the wall of housing 134 is adapted to connect port 136 with port 146 to by-pass the chamber 140. A spring 154 normally positions a ball 156 against a seat 158 formed in passage 152 to close the passage. Spring 154, ball 156 and seat 158 form a check valve for preventing the flow of fluid from port 136 to port 146 while permitting fluid to flow in the reverse direction from port 146 to port 136.

A passage 160 formed in the wall of body 10 connects a passage 162 leading into chamber 12 between head 24 and cap 18 with a bore 164 leading into chamber 14 between dividing wall 16 and stripper and booster piston 38.

Referring now to Figures 1 and 2 to 5, which latter figures illustrate the relative position of the parts at various points in a punching operation, before an operation is begun body 10 and power piston head 24 occupy the relative position shown in Figure 2. When a punching operation is begun the spool 94 of valve 88 is shifted, by any convenient means known to the art, to the left as viewed in Figure 1 to connect pipe 104 with supply pipe 84. At the same time pipe 106 is connected to the tank through pipe 108. The direction of flow of fluid in this condition of valve 88 is indicated by the arrows in Figure 2. Fluid under pressure in pipe 104 urges piston 124 upwardly as viewed in Figure 1 against the action of spring 122 and flows through port 130 and passage 70 into chamber 12. This fluid advances the stripper piston 40 to the right as viewed in Figures 1 and 2. At the same time it moves cylinder body 10 to the right as viewed in the figures to advance the stripper plate 50 and the punch assembly toward the work 60. As is known in the art, the stripper plate 50 engages the work 60 before the punches 58. The increased resistance as the stripper plate engages the work is transmitted through pins 52 and through the stripper piston to the fluid in chamber 12 between wall 16 and piston head 24. As a result of this increased resistance the pressure of the fluid in pipe 104 builds up to cause a similar build-up in the chamber 140 of the valve 132. The relative position of the parts as the stripper plate engages the work is shown in Figure 3.

As the pressure within chamber 140 builds up spool 144 moves upwardly as viewed in Figure 1 to open port 146 to permit fluid to flow from pipe 104 through pipe 138 and through chamber 140 to pipe 148. It will be seen that fluid from the supply pipe now flows into chamber 14 between the head of stripper and booster piston 38 and the tool head 34. This flow of fluid produces two results. First, it acts on the face of stripper and booster piston 38 to shift the stripper and booster piston to the left as viewed in Figure 4 to boost the pressure within the chamber 12 between wall 16 and head 24. The amount by which the pressure of the fluid within chamber 12 increases is proportional to the relative areas of the face of stripper and booster piston 38 and of the face 44 of rod 40. At the same time as fluid entering chamber 14 shifts the stripper and booster piston to the left, it maintains the pressure of stripper plate 50 on the work through the medium of pins 52. The pressure within chamber 12 is built up in the manner described above. The fluid displaced by rod 40 is sufficient to move body 10 to the right as viewed in the figures to drive the punches 58 through the work 60. The relative positions of the parts during the punching operation when the pressure in chamber 12 between wall 16 and head 24 is built up is shown in Figure 4.

At the end of the punching operation in order to return

the parts to their initial positions the spool 94 of valve 88 is moved to the right as viewed in Figure 1 to connect pipe 106 to supply pipe 84 and to connect pipe 104 to the tank through pipe 110. Fluid in pipe 106 flows into chamber 12 between head 24 and cap 18 through passage 72. Fluid flows from chamber 12 through bore 162, passage 160 and passage 164 and chamber 14 to move the stripper piston to the right as viewed in Figure 1. Initial movement of the stripper piston under the action of this fluid relieves the built-up pressure on the fluid between wall 16 and head 24. The piston head 38 continues its movement to the right to engage the stripper pins 52 to maintain stripping pressure on plate 50. At this point in the return operation the punches in the work cause a resistance to movement of cylinder body 10 which results in a build up of pressure within pipe 106. This pressure build up is transmitted through the fluid in pipe 127 to piston 128 to move piston 124 upwardly as viewed in Figure 1 to open port 130 to permit fluid to flow out of chamber 12 through passage 70 and port 130 to the tank through pipe 104. It will be remembered that spring 122 returned piston 124 to seat 120 when spool 94 of valve 88 was moved to the right to initiate a return operation. The direction of flow of fluid during the beginning of a return operation is shown by the arrows in Figure 5. After this connection of passage 70 to the tank, body 10 moves away from the work with tool head 56 to strip the punches from the work. When piston head 38 bottoms on tool head 34 the punches are fully stripped and oil continuing to flow into chamber 12 from passage 72 moves the entire assembly away from the work to its fully retracted position. The assembly is then ready for the next punching operation.

It will be seen that I have accomplished the objects of my invention. I have provided a high pressure hydraulic piercing cylinder with an integral booster and stripping means. My cylinder does not require the external boosters required by assemblies of the prior art. My cylinder accomplishes the punching operation without the flow of high pressure fluid in any pipe external to the cylinder. My hydraulic piercing cylinder is less expensive to construct than systems of the prior art. Further, it is less likely to develop leaks than are systems of the prior art.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is therefore to be understood that our invention is not to be limited to the specific details shown and described.

Having thus described my invention, what I claim is:

1. A hydraulic working cylinder for performing an operation on a workpiece including in combination a cylinder body formed with a power chamber and stripper chamber, a power piston having a head mounted for reciprocation within said power chamber, a tool, a die, means connecting said tool to one of said power piston and cylinder body for movement therewith, means connecting said die to the other of said power piston and cylinder body for movement therewith relative to said tool, a stripper plate, means mounting said stripper plate for movement relative to said tool, a stripper piston disposed in said stripper chamber and having a head and a plunger formed with a face, means providing communication between said face and said power chamber, means for transmitting force from said stripper piston to said stripper plate, a source of fluid under pressure, means for admitting fluid to said power chamber from said source to move said power piston and cylinder body away from each other to move said stripper plate and said tool and said die toward each other, said fluid being adapted to act on said plunger face to move said stripper plate into engagement with said work before said tool engages the work, means responsive to the engagement of said stripper

plate with the work for admitting fluid from said source to said stripper chamber to move said plunger face toward said power chamber to boost the pressure within said power chamber to drive said tool into engagement with the work.

2. A hydraulic working cylinder as in claim 1 including means for admitting fluid into said power chamber to cause said tool and die to move away from each after a forming operation is complete.
10. 3. A hydraulic working cylinder for driving a tool to perform an operation on a workpiece including in combination a cylinder body, means dividing said body into a first chamber and a second chamber, said dividing means being formed with an opening providing communication between said chambers, a power piston disposed within said first chamber, means mounting said power piston and said cylinder body for movement relative to each other, a booster piston disposed in said second chamber and having a portion of reduced cross-sectional area extending into said opening, a source of fluid under pressure, means for admitting fluid from said source into said first chamber to move said piston and cylinder relative to each other, a sequence valve adapted to be actuated to admit fluid from said source to said second chamber, a stripper plate carried by said cylinder body and adapted to be moved into engagement with said workpiece as said cylinder and power piston move relative to each other and means responsive to the engagement of said stripper plate with said workpiece for actuating said sequence valve to admit fluid from said source to actuate said booster piston to boost the pressure within said first chamber.
4. A hydraulic working cylinder as in claim 3 in which said means responsive to the engagement of said stripper plate with said workpiece includes means providing a driving connection between said stripper plate and said booster piston.
5. A hydraulic working cylinder for driving a tool toward a die to perform an operation on a workpiece including in combination a frame, a cylinder body, means dividing said body into a first chamber and a second chamber, said dividing means being formed with an opening providing communication between said chambers, a power piston disposed within said first chamber, means mounting said piston for movement on said frame, means mounting said cylinder for movement with respect to said frame and with respect to said piston, means connecting said tool to one of said power piston and cylinder body, means connecting said die to the other of said power piston and cylinder body, a booster piston disposed in said second chamber and having a portion of reduced cross-sectional area extending into said opening, a source of fluid under pressure, means for admitting fluid from said source into said first chamber to move said piston and cylinder relative to each other to cause said tool to move toward said die and means responsive to a predetermined amount of said relative movement of said piston and cylinder body for admitting fluid from said source to said second chamber to actuate said booster piston to boost the pressure within said first chamber.
60. 6. A hydraulic working cylinder for performing an operation on a workpiece including in combination a cylinder body formed with a power chamber and stripper chamber, a power piston having a head mounted for reciprocation within said power chamber, a tool, a die, means connecting said tool to one of said power piston and cylinder body for movement therewith, means connecting said die to the other of said power piston and cylinder body for movement therewith relative to said tool, a stripper plate, means mounting said stripper plate for movement relative to said tool, a stripper piston disposed in said stripper chamber and having a head and a plunger formed with a face, means providing communication between said face and said power chamber, means for transmitting force from said stripper piston to said stripper plate, a source of fluid under pressure, means for admitting fluid to said power chamber from said source to move said power piston and cylinder body away from each other to move said stripper plate and said tool and said die toward each other, said fluid being adapted to act on said plunger face to move said stripper plate into engagement with said work before said tool engages the work, means responsive to the engagement of said stripper
- 75 plate, a source of fluid under pressure, means for admitting

fluid from said source to said power chamber on one side of said power piston head to move said power piston and cylinder body away from each other to move said stripper plate and tool and said die toward each other, said fluid acting on said plunger face to move said stripper plate into engagement with said work before said tool engages the work, means responsive to the engagement of said stripper plate with said work for admitting fluid from said source to said stripper chamber on one side of said stripper piston to move said plunger face toward said power chamber to boost the pressure within said power chamber to drive said tool into engagement with the work, means for admitting fluid from said source into said power chamber on the other side of said piston to cause said tool and die to move away from each other after a forming operation is complete and means for admitting fluid from said power chamber on said other side of said power piston to said stripper chamber on the other side of said stripper piston head.

7. A hydraulic working cylinder for driving a tool to perform an operation on a workpiece including in combination a cylinder body having a power chamber, a power piston disposed in said power chamber, a tool, a die, means connecting said tool to one of said piston and cylinder for movement therewith, means connecting said die to the other of said piston and cylinder for movement therewith relative to said tool, said workpiece being disposed between said tool and said die, a source of fluid under pressure, a reservoir, a control valve having a pair of outlet ports and adapted to be operated to connect one of said ports to said supply and the other of said ports to said reservoir and to connect said one port to said reservoir and said other port to said supply, a pilot operated check valve for connecting said one port to said chamber on one side of said piston when said one port is connected to said supply to move said piston and cylinder body relative to each other to move said tool and die toward each other, said check valve being adapted to be operated to connect said chamber on said one side of said piston to said one port when said one port is connected to said reservoir, means connecting said other port to said chamber on the other side of said piston, means responsive to an increase of pressure in said chamber on said other side of the piston for operating said check valve when said other port is connected to said supply, said cylinder body having a second chamber and an opening providing communication between said second chamber and said power chamber, a booster piston disposed in said second chamber, said booster piston having a portion of reduced cross-sectional area disposed in said opening, a sequence valve adapted to be operated to connect said one port to said second chamber and means responsive to a predetermined movement of said power piston and said cylinder body in moving said tool and die toward each other for causing a pressure increase in said power chamber on said one side of said power piston for operating said sequence valve to connect said one port to said second chamber, and a check valve for bypassing said sequence valve when said other port is connected to said supply.

8. A hydraulic working cylinder for driving a tool to perform an operation on a workpiece including in combination a cylinder body having a power chamber, a power piston disposed in said power chamber, a tool, a die, means connecting said tool to one of said piston and cylinder for movement therewith, means connecting said die to the other of said piston and cylinder for movement therewith relative to said tool, said workpiece being disposed between said tool and said die, a source of fluid under pressure, a reservoir, a control valve having a pair of outlet ports and adapted to be operated to connect one of said ports to said supply and the other of said ports to said reservoir and to connect said one port to said reservoir and said other port to said supply, a pilot operated check valve for connecting said one port to said chamber on one side of said piston when said one port is connected to said supply to move said piston and cylinder body relative to each other to move said tool and die toward each other, said check valve being adapted to be operated to connect said chamber on said one side of said piston to said one port when said one port is connected to said reservoir, means connecting said other port to said chamber on the other side of said piston, means responsive to an increase of pressure in said chamber on said other side of the piston for operating said check valve when said other port is connected to said supply, said cylinder body having a second chamber and an opening providing communication between said second chamber and said power chamber, a booster piston disposed in said second chamber, said booster piston having a portion of reduced cross-sectional area disposed in said opening, a sequence valve adapted to be operated to connect said one port to said second chamber, means responsive to a predetermined movement of said power piston and said cylinder body in moving said tool and die toward each other for causing a pressure increase in said power chamber on said one side of said power piston for operating said sequence valve to connect said one port to said second chamber, and a check valve for bypassing said sequence valve when said other port is connected to said supply.
